UNITED STATES PATENT OFFICE.

JAMES B. HOGE, OF CLEVELAND, OHIO, AND EDWARD E. CLEMENT, OF WASHINGTON, DISTRICT OF COLUMBIA, ASSIGNEES, BY DIRECT AND MESNE ASSIGNMENTS, TO EDWARD F. COLLADAY, OF WASHINGTON, DISTRICT OF COLUMBIA.

AUTOMATIC RADIO SWITCHING SYSTEM.

Original application filed September 8, 1922, Serial No. 586,842. Divided and this application filed August 18, 1924. Serial No. 732,796.

Our invention relates to radio telephone systems and has for its object the combination of such a system with an electric light, power, or railway system, so that the wires 5 of said system may be employed for controlling and testing, the present case being a division of our copending application Serial No. 586,842, filed September 8, 1922.

In the present case, we attain our object 10 by locating a standard type of radio telephone receiving instrument at consumers' stations on an electric light, power, or railway system, and broadcasting from a central station, which may be the central power 15 station or a substation belonging to the system. The radio operators are provided with switching means whereby they can connect themselves to various radio telephone stations, for purposes of observation and supervision of the system. At the radio telephone 20 stations, we provide switching connections from the instruments to the current mains, and through these connections effect current feed to the filament and plate circuits, and 25 under proper conditions bring to the instruments message bearing current generated by electric waves coming through the ether and intercepted by the outside wire network of the light, power or railway system as an antenna. Since the generation and radiation 30 of these waves is from the central power station, and since the transmitter as well as the substation instruments are grounded, combined ether and wire transmission of the 35 waves will occur, which is highly advantageous for our purpose, according to which the substation instruments are intended for local use only, and are, so far as possible, focused on the one local transmitting station. 40 This central station is provided with amplifying and modulating apparatus for original matter, and with relaying apparatus for distributing to the subscribers or local consumers programmes and other matters received from a distance. By thus organizing 45 the system so that the subscribers are dependent solely on their local central station

for all radio communication, it is possible to unify the service in all respects, and to make service charges on a fair and accurate basis. 50

It is to be understood that the principles herein set forth are not limited as to their embodiment to lighting, power or railway circuits as such, but that any conductor or wire circuit capable of carrying and supplying the necessary current and performing the functions described herein, may be used in the present invention. Among such conductors are telegraph lines, trolley wires, feed wires and cable of lighting, power and 60 railway systems, third rails and underground trolley conductors, and fence and tree wires used by ranchers, lumber interests and others in sparsely settled districts. It is to be further understood that we do not claim herein 65 any specific switching or signalling system, as such systems are well known in the telephone art and can be adapted to perform the functions we have indicated herein by any one skilled in the art, after reading this 70 specification.

Our invention is illustrated in the accompanying drawing which is a typical diagram showing a radio telephone system combined with an electric lighting system. 75

Referring to the drawing, this shows an electric lighting system with a central power station C, five transformer substations, C', C², C³, C⁴, C⁵, consumers' mains M' fed from the substations, and feeder mains M, 80 distributing the power from the main generating plant typified by G to the substations. At the central station Sw indicates the usual main switchboard, and Sw' a supplemental switchboard for purposes to be 85 described. From this board Sw' communication wires 35, 37, 39, 41 extend out to the substations, one pair or more accompanying each feeder cable in the ducts. At each substation a small switchboard Sw² is provided, 90 equipped with an automatic selective switch 36, 38, 40 or 42, having a switch arm or wipers connected to the incoming line 35, 37, 39, or 41, and contacts over which the

wipers are stepped in operation, to connect with local lines to consumers' radio telephone stations. Thus at substation C' the switch 36 has contacts connected to wires 43, 44, which extend from that substation to the radio telephone stations 43, 44^a. This same substation C' carries a feeder main M² to a second transformer station C^c, and the accompanying communication wire 45 extends to a switch 46 at said substation, from which wires 47, 48 extend to radio telephone stations 47^a, 48^a. This subdivision of the system requires an extra digit in the number transmitted from the central station C, the switches 34, 36, and 46 corresponding to first and second selectors and connectors in an automatic telephone system. No detail of the switching circuits or the operating mechanism of the automatic switches is given herein, as such circuits and switches are well known, and of themselves form no part of the present invention, the main features of which as regards the communication circuits, lies in the ability of the central office operator to automatically connect himself to any part of the system through the minimum number of wires, comprising in this case a single pair from the central station to each substation, and single pairs diverging therefrom to the further subdivisions of the system. The last link in any of these circuits is the individual drop wire, extending from a terminal box to the building in which current is to be used. These drop wires are relatively short, and we contemplate employing them for a double purpose, viz, for communication by phone or otherwise over the wires, and as antennæ for the radio telephone instruments, where found expedient or desirable. This will be described hereinafter.

Transformers K are the substation transformers, and transformers K' are the house or pole transformers feeding the consumption circuit M¹⁰ from the house mains M'. The consumption circuits M¹⁰ carry translating devices such as lamps L, and also supply current to the radio telephone receivers RR, to be presently described. These radio telephones are all standardized and of uniform design and construction, and are calibrated and locked when installed, so as to receive on common wave length only, i.e., the wave length allotted to the broadcasting transmitter RT at the central station C. This transmitter may be located at some other point than the central power generating station, and in that case, the switchboard Sw' will obviously be located at the same point, and distribution of the communication circuits effected therefrom. Since the local radio telephone receivers RR are all uniform and fixed as to their tuning, any tuning required must be on the part of the transmitting operator at switchboard Sw', who

is able to listen in and observe the operation of the outlying receiving instruments.

For supervision of the quality of reception, testing, etc., of a subscriber's radio receiver, and controlling the quality of reception, the operator at the central station C make use of the telephone connections to be established through the automatic switching means and circuit connections indicated in Fig. 1 at 32, 34, 35, 36, and 43-44. For example, if the receiving set at sub-station 48^a is to be connected with, the operator at one central station first operates his dial 32 to step the switch 34 around into connection with line 35 leading to sub-central C', then dials again to extend the connection through switch 36 to line 45 leading to sub-central C^c, and again operates his dial 32 to step the switch 46 around into connection with line 48, the individual drop line to switch 48^a. Through the connection thus established the central station operator is enabled to listen in on the audio reproduction of the subscriber's receiver, which observation will enable him to determine what faults are present and the necessary remedies to be applied.

We claim:

1. In a combined electric power distribution and radio telephone system, a central station, distributing circuits carrying current therefrom to points of consumption, radio telephone instruments at said points of consumption, means for connecting said instruments to said distributing circuits for current supply, and a system of telephone intercommunication circuits extending from said central station to said radio telephone instruments with switching means therefor selectively controlled from said central station.

2. In a combined electric power distribution and radio telephone system, a central station, distributing circuits carrying current therefrom to points of consumption, radio telephone instruments at said points of consumption, means for connecting said instruments to said distributing circuits for current supply, and a system of telephone intercommunication circuits extending from said central station to said radio telephone instruments with switching means therefor selectively controlled from said central station.

3. In a combined electric power distribution and radio telephone system, a central station, distributing circuits carrying current therefrom to points of consumption, a plurality of standard radio telephone instruments all tuned to the same wave length located at said points of consumption, means for connecting said instruments to said distributing circuits for current supply, a system of communicating circuits related to said distributing circuits in their subdivision, and extending from a central point to

said radio telephone instruments, a radio broadcast transmitter at said central station arranged to transmit on the wave length to which said standard instruments are

5 tuned, and means associated therewith to selectively switch said communicating circuits so as to connect said central point with

an instrument at any desired point on the system.

In testimony whereof we hereunto affix 10 our signatures.

JAMES B. HOGE.
